UNITED STATES PATENT OFFICE.

EDGAR K. DAY, OF WHEELING, WEST VIRGINIA, ASSIGNOR TO WHEELING CORRUGATING COMPANY, OF WHEELING, WEST VIRGINIA, A CORPORATION OF WEST VIRGINIA.

BRIDGING FOR JOISTS.

1,204,956.

Specification of Letters Patent. Patented Nov. 14, 1916.

Application filed July 8, 1916. Serial No. 108,104.

To all whom it may concern:

Be it known that I, EDGAR K. DAY, a citizen of the United States of America, and resident of Wheeling, county of Ohio, and 5 State of West Virginia, have invented certain new and useful Improvements in Bridging for Joists, of which the following is a specification.

This invention relates to bridging for 10 joists, and it has for its primary object to provide a simple, inexpensive and strong brace or bridging composed wholly of sheet-metal.

A further object of the invention is to 15 provide companion bridging members of sheet-metal, said members being permanently united and adapted to be disposed in crossed relation.

With these and other objects in view, the 20 invention resides in the features of construction which will hereinafter be fully described, reference being had to the accompanying drawings, in which—

Figure 1 is a perspective view of a plurality of joists, showing my invention applied thereto; Fig. 2 is an enlarged plan view of a sheet-metal blank cut and ready for forming; Fig. 3 is a similar view of the shaped members; Fig. 4 is a perspective view of the 25 invention, the members being shown in crossed relation, as when applied to adjacent joists; and Fig. 5 is an enlarged section on line 5—5, Fig. 4.

Referring to said drawings, in which like 30 designating characters distinguish like parts throughout the several views—1 and 2 indicate bridging members composed of sheet-metal and each of which is substantially V-shaped in cross section, as shown in Fig. 5.

Said members are adapted to be disposed in 35 crossed relation and to be mounted in inclined cross-bracing position with respect to adjacent joists 3 of a building structure, each of said members having its opposite ends 40 flat in form and inclined at an angle to the axis of its body so that they are adapted to seat for attachment upon the opposing faces of adjacent joists at points adjacent to the upper and lower edges, respectively, of the

latter, as shown in Fig. 1. Said members 1 50 and 2 are preferably composed of a single sheet-metal blank of the rectangular form shown in Fig. 2, two longitudinal incisions 5 being produced at opposite sides of the median line of the blank and extending from 55 opposite ends to points somewhat past the midway point of the blank. A slender centrally disposed unsevered portion or tie 6 is thus left which connects the two parts of the blank, which parts are then shaped to form 60 the two members 1 and 2 which are then permitted to remain in parallel relation, as shown in Fig. 3, until such time as they are to be applied for use, when they are relatively turned to occupy substantially the positions shown in Fig. 4. As is obvious, the tie 6 serves to retain the members in their proper relation when the last-mentioned positions are assumed.

What is claimed is—

1. A bridging composed of a single sheet-metal blank and consisting of a pair of similarly shaped brace members formed by two longitudinally disposed incisions produced at opposite sides of the median line of 75 the blank and extending from opposite ends to points slightly past the middle of said blank, to leave a slender unsevered portion whereby said members are permanently connected, said members being adapted for 80 turning into relatively crossed relation.

2. A bridging for joists consisting of a pair of similarly shaped brace members cut from a single sheet-metal blank, said members being disposed edge to edge in parallel 90 alinement, and a slender unsevered integral connecting tie disposed intermediate said members substantially midway between their ends, said members being adapted to be disposed in relatively crossed position with said 90 tie maintaining their closely associated relation.

In testimony whereof, I affix my signature in presence of two subscribing witnesses.

EDGAR K. DAY.
